VAPORIZING DEVICE

Charles F. J. Dupuy, Mahwah, N. J., assignor to
O-Cedar Corp'n, Chicago, Ill., a corporation of
Illinois

Application December 9, 1944, Serial No. 567,379

3 Claims. (Cl. 299—20)

1

This invention relates to vaporizing device and more particularly to devices adapted for domestic use to vaporize perfumes, deodorants, disinfectants or the like.

One of the objects of the invention is to provide a vaporizing device which is extremely simple and inexpensive to manufacture and which will effectively vaporize various types of liquids.

Another object of the invention is to provide a vaporizing device in which the container for the liquid to be vaporized can easily be replaced without the necessity of replacing the entire device.

Still another object is to provide a vaporizing device in which the rate of vaporization may readily be controlled.

The above and other objects and advantages of the invention will be more readily apparent from the following description when read in connection with the accompanying drawing, in which—

Figure 1 is a side elevation of a vaporizing device embodying the invention;

Figure 2 is a central section on the line 2—2 of Figure 1; and

Figure 3 is a horizontal section on the line 3—3 of Figure 1.

The device comprises a tubular shell 10 which is preferably cylindrical and is opened at its top and bottom. The shell 10 as will appear hereinafter may be a permanent unit not requiring replacement and, therefore, may be decorated or ornamented in any desired manner. The shell may be made of any desired material but is shown as formed of sheet metal and is provided adjacent its lower end with an inwardly turned bead 11 forming an internal annular flange spaced slightly above the bottom of the shell. The top of the shell is formed with an external flange or bead 12 to support a cover and is provided between the bead 12 and the upper edge of the shell with a series of spaced openings 13.

The shell is adapted to receive and support a container for liquid to be vaporized shown as a bottle 14 terminating at its top in a reduced threaded flange 15. A wick 16 is mounted in the container and as shown has an upper flat pad portion substantially filling the neck 15 with legs depending therefrom to the bottom of the container to feed liquid to the pad portion. The wick may be formed with one or more legs as shown and as more particularly described and claimed in my copending application, Serial No. 558,631, filed on October 20, 1944.

During shipment and storage the container 14

2

is adapted to be closed by a threaded cap 17 having threads rolled in its main body portion to engage with the threads on the neck 15 and terminating at its open end in a rolled bead 18 of greater external diameter than any other portion of the cap. In use, the cap is removed from the bottle 14 and is dropped into the shell in inverted position as shown in Figure 2, so that the bead 18 will engage the bead 11 to support the cap in the shell. The bottle may then be placed in the shell above the cap with its bottom outer edge resting on the bead 18 and with its top open to expose the upper pad portion of the wick 16 to the interior of the shell. In the event it is desired to discontinue operation of the device, the cap 17 may be replaced on the container, any possibility of loss being avoided by maintaining the cap in the shell at all times.

The level of liquid in the container 14 may be observed at all times thru vertically extending slots 19 formed in the opposite sides of the shell. By looking thru the slots 19 toward a source of light, an observer can easily determine the amount of liquid remaining in the container and can be informed when refilling or replacement of the container is necessary. When the container in use is empty, it may be removed from the shell and replaced by a new container filled with liquid without the necessity of replacing the shell.

In order to control the rate of vaporization a flanged cover 21 is provided for the shell having a downwardly turned flange 22 adapted to overlie the shell and to terminate adjacent the bead 12. The flange 22 is formed with a series of openings 23 of substantially the same size and spacing as the openings 13 in the shell so that as the cover 21 is turned, the openings 13 and 23 will be moved more or less into register to regulate communication between the interior of the shell and the atmosphere. For full vaporization the cover 21 may be removed from the top of the container and placed over the bottom of the container for convenience. At this time, the full area of the wick 16 is exposed to the atmosphere and maximum vaporization will occur. For a slower rate of vaporization, the cover may be placed on the top of the container as shown and turned to regulate the effective size of the openings 13.

While one embodiment of the invention has been shown and described in detail herein, it is to be understood that this is illustrative only and is not intended to be taken as definition of the scope of the invention, reference being had for this purpose to the appended claims.

What is claimed is:

1. A vaporizing device comprising a tubular shell open at its ends and having an inwardly projecting bead adjacent its bottom, a container adapted to hold liquid to be vaporized fitting within the shell, a cap for the container having a bead adapted to rest on the bead in the shell with the major portion of the cap lying below the bead, and a wick in the container adapted to be exposed adjacent the top of the container.

2. A vaporizing device comprising a tubular shell open at its ends and having an inwardly projecting bead adjacent its bottom, a container adapted to hold liquid to be vaporized fitting within the shell, a cap for the container having a bead adapted to rest on the bead in the shell with the major portion of the cap lying below the bead, a wick in the container adapted to be ex-

posed adjacent the top of the container, and a flanged cover for the shell, the cover flange and the side wall of the shell adjacent the top being formed with spaced openings adapted to register more or less when the cover is placed over the top of the shell.

3. A vaporizing device comprising a tubular shell open at its ends and having an inwardly-projecting bead adjacent but spaced from its bottom, a container cap having a bead adapted to rest on the bead in the shell, a container resting upon said cap bead within said shell, and a removable closure for the top of said shell, said cap being removable through the upper part of said shell and adapted to be placed upon said container to close the same when said container is placed upon the bead in said shell.
